UNITED STATES PATENT OFFICE.

WILLIAM LANG, OF BROOKLYN, NEW YORK.

PROCESS OF MANUFACTURING WATCH-CASES.

SPECIFICATION forming part of Letters Patent No. 365,826, dated July 5, 1887.

Application filed October 20, 1886. Serial No. 217,619. (No model.)

To all whom it may concern:

Be it known that I, WILLIAM LANG, of the city of Brooklyn, in the county of Kings and State of New York, have invented certain new and useful Improvements in the Manufacture of Watch-Cases, of which the following is a description sufficient to enable others skilled in the art to which the invention appertains to make and use the same.

10 My improvements relate to the manufacture of the main parts of a watch-case frame—the center, back, and bezel—without seam or joint, out of pieces of sheet metal.

15 My main object is to simplify and cheapen the construction of parts, and at the same time render them more accurate in shape and fit than heretofore.

20 I am aware that dies have heretofore been used for the purpose of shaping the sheet metal parts of watch-cases, and I do not herein seek to cover such use, broadly, as a part of my improved process of manufacture, my invention consisting in carrying out, relatively and successively, or substantially so, the several 25 steps in the process hereinafter set forth. Of course it is obvious that the identical order herein described and shown is not absolutely essential, since the succession, and in some cases the operations themselves, may be varied 30 without deviating from the spirit or intent of my invention.

35 In the accompanying drawings I illustrate the effect of the succeeding operations in my process, although it is to be understood that I do not limit myself to the precise form of parts shown, since the latter will vary more or less, according to the particular size or style of watch-case required.

40 Figure 1 represents a front view of a watch-case made in accordance with my improved process, with pendant and tube added. Figs. 2 to 8, inclusive, represent, respectively, diametrical sections of the "center" or frame of the case at the end of succeeding operations. 45 Figs. 9 to 13, inclusive, represent the results of succeeding operations in the formation of the back or cap. Figs. 14 to 23, inclusive, represent the results of the operations in constructing my new form of bezel with mat. 50 Fig. 24 represents a diametrical section upon plane of line $\alpha\alpha$, Fig. 1. Fig. 25 illustrates the old formation of groove in bezel.

The watch-case A shown is of the kind in which the back B and bezel C are held upon the center D by the closeness of the fit between the "snaps" or rims of the back and bezel, and the opposed receiving-surfaces upon the center D, hinging being thereby dispensed with, although the process is equally applicable to the manufacture of watch-cases, the parts of which are to be hinged together.

55 The preparatory operations upon the blank for the center D consist in severing a disk of suitable size from a sheet of metal of the desired thickness, drawing or cupping it, and then piercing it centrally, leaving it in the form shown in Fig. 2, all by the use of ordinary dies adapted for such purpose. In fact, all of the dies used in connection with my improved process are simply modifications of the ordinary kinds of dies used for similar purposes, and I do not confine myself to the use of any special construction of die. The blank D, being thus shaped with the cylindrical portion d and the inwardly curved flange d' , is 70 next subjected to the action of dies, which crimp the said flange d' in such manner as to form the interior and exterior annular shoulders, d^2 d^3 , as indicated in Fig. 3. The edge of the cylindrical portion d is next bent and 75 curved inward by the use of suitable dies to afford the exterior shoulder, d^4 , two (or more) separate compressions being desirable, as indicated by Figs. 4 and 5, in order to effect the change in the shape without injury to the 80 blank. The next step is that of truing the exterior central portion, d^5 , to a uniform convex surface by means of a concave cutting-tool in any ordinary turning-machine, leaving the blank as shown in Fig. 6. The blank D is 85 next supported externally in the lathe and the edge 1 turned true. Next, the inner edge, 2, is turned to render it true and increase the diameter of the opening upon that side to the standard size. Then the cutter is passed in 90 from the opposite side of the blank and the interior surfaces, 3, trimmed and rendered even with each other; and, finally, this step of shaping the interior is completed by turning the annular groove d^6 , near the back edge 95 of the center piece, D, for the purpose of affording a means of securing the works of the watch in place in cases in which it is designed to use such method of attachment. The blank 100

or center piece, D, is once more supported upon the lathe internally and the parallel surfaces 4 and 5 simultaneously cut upon either side of the convex middle portion, d^1 , and the exterior surfaces, 6 and 7, of the opposite flanges, d^1 and d^2 , trimmed to the standard size and into slight convexity in order to facilitate the application of the back and bezel and insure a tight fit with their rims or snaps.

10 It is obvious that the order in which the several cuts are to be made in trimming this and the other parts of the watch-case may be varied according to preference or convenience, as I have herein simply followed in my description a preferable mode of procedure. The blank back B, having been first cut and then drawn by a compound die into the shape shown in Fig. 9, next has its flange b bent inward at an angle of about forty-five degrees, as shown in Fig. 10, the succeeding operation completing the turning over of the said flange, so that it projects inward in a plane substantially at right angles to the axes of the back plate, B. The latter is next supported both internally and externally in a turning-machine, and the outer surface, b' , Fig. 12, and inner or snap edge, b^2 , Fig. 13, trimmed off to the required degree, the diameter of the opening formed by the edge b^2 being such that the said edge fits over the flange d^1 of the center D so closely as to bind thereon with sufficient pressure to hold the said parts together.

I am aware that snap-flanges have heretofore been formed by bending over the edge of the back piece and treating it in such manner as to thicken and thereby strengthen the metal composing the snap; but I do not set claim to any process of thickening or compressing the metal at that point, confining myself to the simpler and more inexpensive method of bending over the edge of the back piece and subsequently truing the outer surface and inner edge thereof. The snap thus formed, being designed more especially for the purpose of obviating the use of hinges or positive means of attachment to the center piece, has an advantage over the thicker rims referred to, which are designed expressly to render practicable the hinging of the parts, the greater elasticity of the snap constructed according to my method adapting it to retain itself in place upon the center piece more effectively, and for a like reason facilitating its application to or removal from the said center.

55 In forming my improved form of bezel-piece or front C for the reception of the watch-crystal the shell is first cut and drawn into the shape shown in Fig. 14 by the same dies used in the preparatory step upon the blank for the back, the result of which is shown in Fig. 9. The blank is next pierced centrally by a die, which removes a disk of metal very nearly equal in diameter to the opening required for the watch-crystal, the next operation being to trim off the edge c to standard size and to impart to it a slight inward bevel.

Heretofore the groove or seat for the edge

of the glass or crystal has been turned in the edge c of the bezel, metal of sufficient thickness to admit of such an operation having to be used. In Fig. 25 a cross-section of a portion of one side of such old form of bezel is shown, with the beveled groove turned in its edge, and representing also the angle to which the inner edge, c' , is bent inward in order to properly shape the groove or seat for the reception and support of the edge of the glass and form the beveled visible mat-surface. In practice the operation of bending inward this inner edge, c' , is a delicate operation and liable to break or injure it, so that the bezel is useless. I obviate this difficulty by making my bezel in two parts, the inclined internal shoulder, c' , being formed of the inner edge of a mat-piece, C', which is inserted and secured within the bezel-piece C, substantially as hereinafter set forth.

In forming the mat C' a flat annular blank (shown in Fig. 17) is first stamped out of thin sheet metal and then pressed into the shape shown in Fig. 18. The succeeding operation, which consists in removing the surplus material by means of suitable cutting-dies, leaves the mat C' ready for insertion within the shell C of the bezel. The parts C' C are accordingly placed together between dies which turn over the outer edge, c^2 , of the bezel upon the outer edge, C, of the mat C', two or more operations being preferable to accomplish this, as indicated in Figs. 20 and 21, as in the case of the corresponding step in the process of turning over the edge of the back B to form the snap. In fact, the flange c^2 constitutes the snap for the bezel, and is finished by turning off its outer surface, c^3 , and inner edge, c^4 , Figs. 22 and 23, in precisely the same manner that the said snap of the back B is finished, as hereinbefore described, and illustrated in Figs. 12 and 13. The bezel thus formed is cheaper and stronger than the old form of bezel, and also affords a more perfect seat for the glass, the edges of which are beveled and sharply defined, so that the corresponding sharply-defined angular groove or seat in my bezel affords a more perfect fit than heretofore, the glass being simply forced or snapped into place against the elasticity or spring of the metal constituting the beveled front edge of the bezel and sustained at the rear by the flange of the mat. By this construction I am also enabled to make the flange of the mat, which is visible through the glass, of any desired width, and thereby improve the appearance of the watch-front.

What I claim as my invention, and desire to secure by Letters Patent, is—

1. The process of manufacturing the parts of a watch-case from sheet metal, consisting in treating the blanks to operations relatively and substantially such as herein described.

2. The process of shaping the center piece of a watch-case, substantially as herein set forth, consisting in proximately shaping the blank by means of dies and subsequently re-

moving the surplus material and finishing by turning, substantially in the manner and for the purpose described.

3. The process of forming the cap or back 5 of a watch-case, substantially as herein set forth, consisting in shaping the blank and turning over its edges to form the snap by means of dies, and subsequently treating the snap to the turning operations, substantially 10 in the manner and for the purpose described.

4. The process of forming watch-case bezels, substantially as herein described, consisting in shaping the outer shell by means of dies and turning its inner edge, substantially 15 as described, inserting a mat formed substan-

tially as described, and securing the two parts together by bending over the outer edge of the shell to form the snap, substantially in the manner and for the purpose described.

5. The process herein described of securing 20 the flanged mat within the outer shell of the bezel, consisting in placing the mat within the shell and then turning the outer edge inward to form the snap, substantially in the manner and for the purpose described.

WILLIAM LANG.
